United States Patent Office.

JOHN P. PEARS, OF PITTSBURG, PENNSYLVANIA.

Design No. 4,641, dated February 7, 1871.

DESIGN FOR MOLDS FOR LAGER-BEER GLASSES.

The Schedule referred to in these Letters Patent and making part of the same.

To all whom it may concern:

Be it known that I, JOHN P. PEARS, of the city of Pittsburg, in the county of Allegheny and State of Pennsylvania, have invented a new and useful Design for Mold for Lager-beer Glass; and I do hereby declare the following to be a full, clear, and exact description thereof, reference being had to the accompanying drawing making a part of this specification, which represents a sectional view of a drop-mold, and illustrates my improved design.

To enable others skilled in the art to make and use my improved design, I will proceed to describe the same.

The mold-cavity *a* is made in any of the ways known to the art, in either a two-part or solid mold, in the latter case tapering sufficiently to admit of the removal of the article when pressed.

From the lower end of the cavity, extending ver-

tically up its sides, are the beads *b*, in any desired number, and arranged at a little distance apart, such beads tapering toward the end, and terminating near or a little above the middle of the cavity. These beads make a corresponding series of grooves in the face of the glass.

Between the lower end of each two beads *b* is an oval-shaped convex, *c*, which convexes make in the glass a corresponding series of concaves.

What I claim as my improved design, and desire to secure by Letters Patent, is—

In the glass-mold cavity *a*, the beads *b* and convexes *c*, substantially as described and shown.

In testimony whereof I, the said JOHN P. PEARS, have hereunto set my hand.
